UNITED STATES PATENT OFFICE.

CLARENCE E. REED, OF HOUSTON, TEXAS.

PIPE-TONGS.

1,316,185.

Specification of Letters Patent. Patented Sept. 16, 1919.

Application filed June 21, 1918. Serial No. 241,152.

To all whom it may concern:

Be it known that I, CLARENCE E. REED, a citizen of the United States, resident of Houston, Texas, have invented certain new 5 and useful Improvements in Pipe-Tongs, of which the following is a specification.

My present invention relates to pipe tongs or wrenches and is designed more especially for handling the pipe used in oil wells, 10 though not limited to such use.

The invention includes the novel features of construction and arrangement and combination of parts hereinafter described and particularly defined by the appended claims, 15 an embodiment of my invention being illustrated in the accompanying drawing in which:—

Figure 1 is a plan view of the tongs.

Fig. 2 is an edge view of the same.

20 Fig. 3 is a sectional plan view illustrating a modification, and

Fig. 4 is a detail view of a further modification.

Referring to these drawings by reference 25 characters, the numeral 1 designates a main jaw which is preferably provided with a curved face 1^a adapted to conform approximately to the curvature of the pipe upon which the tongs are used. This jaw is provided with a suitable handle 2 rigidly connected thereto and it is provided at or near 30 its forward end with a pipe engaging or gripping member or projection a. 3 designates the movable jaw which also has a 35 curved face provided with a plurality of pipe gripping or engaging projections, two being shown as my preferred arrangement designated respectively as b and c, these being spaced apart and located respectively 40 at or near the opposite ends of the movable jaw. Link means are provided for connecting the movable or supplemental jaw 3 to the main jaw 1 and such means preferably takes the form as shown in the drawings of

45 a pair of links 4 which have a curved portion 4^a to enable the edges of the links to be clear of the pipe. These links are pivotally connected to the main jaw by a pivot pin 6 and to the supplemental jaw by a pivot 50 pin 7. These pivot pins are so located that a line connecting their axes will preferably pass to the outside of the gripping projection b, or in other words, will intersect the periphery of the pipe and furthermore the 55 axis of the pivot pin 7 is preferably located

nearer to the gripping projection c than it is to the gripping projection b. This arrangement of the pivot pins with respect to the gripping projections is such that the pivot of the smaller jaw is off-centered with 60 relation to the line of pressure of the gripping point of the larger jaw, or in other words, a line drawn from the axis of the pivot 7 to the gripping projection a will pass to one side of the center of a circle including 65 the three gripping points a, c and b, or to one side of the axis of the pipe when in place between these three gripping projections. This insures a quick and sure grip of the pipe as the pressure strikes the point 70 b of the supplemental jaw when the tongs are pushed against the pipe. When the jaws have thus been caused to encircle the pipe movement of the handle to the left 75 tightens the engagement and effects the turning of the pipe.

In order to effect the quick release of the pipe I provide the main and movable jaws with parts designed to contact and effect the release of the pipe or the opening of the 80 jaws and this may take the form of a shoulder 1^b on the main jaw adapted to bear against a corresponding part or a shoulder 3^b on the supplemental jaw when the handle is moved to the right.

To prevent any binding of the links on the main jaw I prefer to recess the sides of the main jaw as indicated at 1^c and provide such recess portions with bosses 1^d against which the links are held by the pivot pins 85 6, thus reducing friction and facilitating the relative movement of the links and jaw.

The handle 2 may be integral with the main jaw 1 but I prefer to make it detachable and connected to the main jaw by a 90 bolt 8 and nut 9 or other suitable securing means so that the same handle may be used for different sized wrenches or tongs.

As these tongs are of considerable weight and require frequent use I preferably provide means for sustaining them from some fixed support and to this end provide the handle with a slip ring 10 to which is secured a clevis 11 for the connection of a chain or other supporting device, the slip 105 ring enabling the tongs to be turned over or inverted according as to whether a right-hand or left-hand gripping action is desired.

In some instances I find it desirable to provide spring means for assisting the grip- 110

ping action of the jaws and a convenient arrangement of such spring means is shown in Fig. 3.

According to this construction a hole 12 is drilled through the main jaw approximately centrally of its two sides, and is counterbored or enlarged for a suitable distance, as indicated at 12^a. Within the enlarged portion is mounted a compression spring 13, which bears at one end against the shoulder formed by the enlargement and at the other end against a washer 14 held in place on the threaded stem of the T-bolt 15 by a nut 15^a. The cross bar 15^b or arms of the head of the T-bolt engage holes or recesses in the links 4 and thus the spring tends to rock said links about the pivot 6, and press the movable jaw toward the main jaw. The action of this spring 20 will cause the jaws to close with a snap and instantly grip the pipe when applied thereto. The tension of the spring may be adjusted by means of the nut, and in actual practice very slight amount of compression 25 on the spring will be sufficient to secure the desired results.

Instead of using a spring between the main jaws and links I may use a spring between one or each of the links and the 30 movable or supplemental jaw, as shown in Fig. 4. Such spring may be in the form of a coil spring 13^a having its ends connected to pins located respectively on the link or links and on the movable jaw, the latter 35 being conveniently located adjacent the gripping projection 3.

It will be obvious that the springs used 40 may be either compression or tension springs, as desired. If desired the springs 40 may be used in the same tongs, one between the links and main jaw and the other between the links and supplemental or movable jaw.

Having thus described my invention what 45 I claim is:—

1. A pipe tong or wrench comprising a main jaw, a suitable handle rigidly connected thereto, said main jaw having a concave recess in one side face thereof, the extremities of said concave recess lying in substantial alinement with said handle, said concave recess having a pipe engaging projection at its outer extremity, a supplemental convex jaw having a curved face 50 provided with pipe engaging projections at or near its extremities, and link means pivotally connecting the supplemental jaw to the main jaw.

2. A pipe tong or wrench comprising a main jaw, a suitable handle rigidly connected thereto, said main jaw having a con-

cave recess in one side face thereof, the extremities of said concave recess lying in substantial alinement with said handle, said concave recess having a pipe engaging projection at its outer extremity, a supplemental curved jaw having a curved face provided with pipe engaging projections at or near its extremities, and a link having one end pivotally connected to the main 65 jaw and the other end pivotally connected to the supplemental jaw intermediate of the pipe engaging projections thereof.

3. A pipe tongs or wrench comprising a concave main jaw having a pipe engaging projection at or near its outer end, a supplemental concave jaw having a plurality of pipe engaging projections, a link pivotally connected to the main and supplemental jaws, said pivots being so located that a straight line connecting their axes will pass to the outside of but in proximity to the innermost projection of the supplemental jaw.

4. A pipe tongs or wrench comprising a concave main jaw having a pipe engaging projection at or near its outer end, a supplemental concave jaw having a plurality of pipe engaging projections, a link pivotally connected to the main and supplemental jaws, said pivots being so located that a straight line connecting their axes will pass to the outside of but in proximity to the innermost projection of the supplemental jaw, and a shoulder on the main jaw 90 arranged to bear on a corresponding part of the supplemental jaw for opening the jaws.

5. A pipe tongs or wrench comprising a main concave jaw having a pipe engaging tooth near its outer end, a suitable handle rigid therewith, a supplemental concave jaw carrying a pair of spaced pipe engaging projections, a link pivotally connected respectively with the main and supplemental jaws, the point of pivotal connection with the supplemental jaw being relatively nearer the outer projection of the supplemental jaw than the inner projection.

6. A pipe tongs comprising a main jaw 110 having a suitable handle, a supplemental jaw, a pair of links connecting said jaws on opposite sides, a T-bolt having its head pivotally connected to said links, and its shank lying in a passage in the main jaw, 115 a spring encircling said shank and bearing against a fixed abutment, and a nut on said shank for confining the spring.

In testimony whereof, I affix my signature.

CLARENCE E. REED.
